UNITED STATES PATENT OFFICE.

LOUIS H. MORIN, OF NEW YORK, N. Y., ASSIGNOR TO A. S. PHILLIPS, OF NEW YORK, N. Y.

MACHINE FOR MAKING PYJAMA FROGS.

Application filed August 13, 1926. Serial No. 129,076.

This invention relates to a machine for making frogs or button hole loops commonly used on pyjamas, dressing gowns and similar garments. These frogs are made from a specially woven tape or braid provided along its edges with cords slideable within the woven fabric of the tape. The tape is curved flatwise to form the characteristic loops by pulling one of these cords while holding the other fixed relative to the tape, the contour and position of each loop being determined by the length of cord pulled and the place at which the fixed cord is held. So far as I am aware all pyjama frogs today are made by hand and although the operators acquire a high degree of skill it is difficult to reproduce hundreds of these frogs of exactly the same pattern, and besides, as is usually the case with hand labor the output is relatively small. It is the object of the present invention to provide a machine for making these frogs.

In the machine which I have designed, a unit length of tape is held in position by a plurality of spaced grippers which press against one of the cords only while a moving member pulls the other cord. As the successive loops are made the grippers are released one by one by means synchronized with the moving member, thus changing the effective point at which the fixed cord is held, whereby a frog of exact and predetermined design is made. In order to make the machine automatic and continuous in its operation I utilize the moving member which pulls the cord during the looping operation, to unwind the tape from a spool and draw it under the grippers, and, in view of the fact that during the looping operation the moving member must pull on one of the cords only, I cause it to draw the tape into position under the grippers through a pull exerted on this same cord. The machine is thus all set for the looping operation as soon as the grippers engage the tape. I also employ means for automatically cutting off each unit length of tape just before the looping operation and means for severing the extending cord from the completed frog. In order to insure that the moving pulling member grips its proper cord only and not the fabric of the tape, I have provided a finger which strips the fabric from the forward end of the tape after

each cutting thus leaving the cord exposed and in readiness to be seized.

In my co-pending application Serial No. 129,075 filed concurrently herewith I have illustrated and described a machine in which a single but movable gripping member is employed. Except for this and the differences in the mechanisms for operating these two types of grippers, the two machines are identical.

In the accompanying drawings I have illustrated a machine embodying the principles of my invention. It is to be understood, of course, that this machine might be modified in many respects and still embody the invention, this being particularly true of the operating mechanism illustrated. In these drawings, Figure 1 is a plan view of the machine; Figure 2 is a transverse vertical section on an enlarged scale taken along line 2—2 of Figure 1; Figure 3 is a front elevation of the machine; Figure 4 is a section taken along line 4—4 of Figure 3; Figure 5 is an enlarged detailed section along line 5—5 of Figure 1; Figure 6 is a detailed section taken along line 6—6 of Figure 5; Figure 7 is a horizontal section taken along line 7—7 of Figure 2 and Figures 8, 9, 10, 11, 12, 13 and 14 are views of the frog in various stages of manufacture, Figure 14 being a view of the completed frog.

The machine illustrated in these drawings comprises a base 1 on which are mounted a plurality of standards 2 which support the various operating elements of the machine. A bracket 3 is secured to the left-hand standard and carries a spool 4 which supplies the tape 5 from which the frogs are made. The tape from this spool is unwound, cut off in unit lengths and formed into loops of the desired curvature and position to form the completed frog. Power is supplied to the machine through a pulley 6 to which the main shaft 7 of the machine is connected and disconnected by means of a clutch 8 controlled by a clutch arm 9. I shall first describe the mechanism for drawing the unit length of tape from the spool.

Extending across the front of the machine is a horizontal track or guide-way 10, T-shaped in cross section, upon which is mounted a carriage 11 which is moved back and forth along this guide-way by means of a

link-work consisting of five inter-connected links 12, 13, 14, 15 and 16, the links 14 and 16 being pivotally mounted upon the fixed bosses 17 and 18. Fixed upon the shaft 7 is a cylindrical cam drum 20 provided with a peripheral cam groove 21. The link 16 is provided with a cam follower 22 extending within the cam groove 21, and the reciprocation of the carriage 11 is thus controlled by the cam drum 20. The link 12 which is pivotally connected with the carriage 11 terminates in a dog 24 fixed relative to the link 12 so that when the carriage is moving toward the right, Figure 1, the dog 24 is swung clockwise and into contact with a plate 25 forming a part of the carriage. When the carriage 11 is moved toward the left, the dog 24 is swung counter-clockwise out of contact with the plate 25, but limited in its counter-clockwise swinging by means of a suitable stop 26 on the carriage which engages the link 12.

The tape 5 as it leaves the spool extends through a guide-slot 27 in the bracket 3 and into the space between the dog 24 and the plate 25 when the carriage is in its extreme left-hand position, as shown in Figure 1. The cam drum 20 then moves the carriage to the right, acting through the various connecting links described above, and swings the dog 24 inward to seize the lower of the two edge cords of the projecting tape, as shown most clearly in Figure 2. Continued movement of the carriage toward the right draws a unit length of tape across the machine and after this unit length has been severed from the tape on the spool, the machine is in readiness for the looping operation. I shall now describe the means for cutting off this unit length of tape which has been drawn into looping position.

Pivottally mounted at 28 upon the left-hand standard 2 of the machine is a pair of shears 29, the cutting plane of which is just within the extreme left-hand position of the dog 24. These shears are operated by means of a cam disk 30 fixed upon the shaft 7 and provided with a facial cam groove 31 in which is positioned a cam follower 32 mounted upon the ends of a bell-crank lever 33 pivotally mounted upon the standard 2 at 34, the other arm of which is connected to the shears through links 36. Cam 30 is so designed that when the carriage has unwound a predetermined unit length of tape, the shears 29 operate to sever this unit length from the tape on the spool but leave the forward end of the new tape in position to be gripped by the carriage on its return movement. The shearing action just described does not take place, however, until the unit length of tape has been securely gripped in position for looping, and I shall now describe the gripping means.

Extending across the front of the machine

and supporting the guideway 10 is a plate 38 provided with a longitudinal slot 39 extending substantially across the machine. An angle-iron 40 mounted upon the upper rear face of the plate 38, extends across the machine and is likewise provided in its horizontal flange with a longitudinal slot 41 co-extensive with the slot 39. The angle-iron 40 supports a plurality of grippers 42 each provided at its forward end with a depending finger 43 and each slidably mounted within an inverted U-shaped supporting member 44 secured to the horizontal flange of the angle iron by means of a setscrew 45 extending through the slot 41. The forward end of each gripper extends through the slot 39 and the finger 43 is urged into contact with the plate 38 by means of a coil spring 46.

Keyed upon the shaft 7 are a plurality of cam discs 47, one for each of the grippers 42. Each gripper supporting member 44 is provided with two rearwardly extending flanges 48 which receive one of the cams 47 so that each gripper with its supporting member 44 and cam 47 constitutes a unit which may be moved bodily longitudinally of the machine and fixed in any desired position by means of the setscrew 45. Each spring 46 holds the inner ends of its gripper 42 against the peripheral face of its cam and each cam is provided with a cut-out 48 which, as the shaft 47 is rotated, results in a reciprocation of the gripper. The cut-outs in the successive cams are so designed that the grippers are moved outward from the plate 38 in succession beginning with the left-hand gripper.

When the carriage 11 is drawing the unit length of the tape across the machine, the pull, as explained above, is exerted through the lower edge cord. During this movement the fingers 43 of the grippers 42 are held in their outermost position by the cams 47, as illustrated most clearly in Figure 2, and the outer edge cord is passed between them and the plate 38. As soon as the desired length of tape has been unwound, the forward ends of the cam cut-outs 48 simultaneously permit the springs 46 to move the grippers toward the rear to grip the upper edge of the tape and hold it against the plate 38. The tape is thus securely held, the shearing action immediately follows and the tape is in position for the looping operation which I shall now describe.

The left-hand gripper grips the left-hand end of the tape somewhere intermediate its ends, but close to the left-hand end, so that further movement of the carriage 11 to the right pulls the lower edge cord, curving the left-hand end of the tape as illustrated in Figure 8. To form a single loop of the desired curvature and to form a plurality of such loops in proper spaced relation, it is

necessary to move forward the effective point at which the tape is gripped. This is automatically accomplished by the cams 47 which release the grippers 42 in timed sequence as explained above, each gripper holding the tape until the forward movement of the carriage 11 has effected the desired curvature of that portion of the tape lying to the left of the gripper. The curve 10 illustrated in Figure 8 is made before the first gripper is released; the curve of Figure 9 after the first gripper has been released but before the second has been released; and the completed loop of Figure 10 is made 15 after the first two grippers have been released, but while the third is still holding the tape against the plate 38. The relatively greater space between the third and fourth grippers permits the formation of the second 20 loop in proper spaced relation to the first, as illustrated in Figures 11 and 12. And so on until the completed frog is made.

At the conclusion of the looping operation the lower edge cord extends beyond the end 25 of the tape and should be cut off. This is accomplished by means of a knife 60 pivoted at 61 on the right-hand standard 2 co-operating with a shear blade 62, and operated by means of an arm 63 carrying a cam roller 30 64 which is controlled by a cam 65 on the peripheral face of the cam drum 20. This cam is so timed that when the frog has been completed, the extending cord is severed and the completed frog deposited upon an off- 35 bearing belt 66, operated by means of a chain and sprocket connection 67 from the shaft 7. The frogs thus looped are complete except for a light stitching designed to keep them in proper shape during packing and ship- 40 ping.

The cycle just described is now repeated, the carriage 11 being moved to the left in position to seize and unwind a new unit length of tape and the grippers extending 45 outward from the plate 38 and in readiness to grip the new unit length at the beginning of the looping operation. It is necessary, however, that the dog 24 should seize only the lower edge cord of the new tape, as 50 otherwise when the looping operation begins and the tape itself is held stationary, the fabric would be torn. I shall now describe the mechanism for preparing the forward end of the new tape for seizure by the dog 24.

Pivoted on the bracket 3 and beyond the shears 29 is an arm 68 provided at its inner end with a finger 69 designed to be swung against the fabric of the forward end of the 55 tape between the two edge cords, but normally held out of contact with the tape by means of a spring 70 connecting the outer end of the arm 68 with an extension on the bracket 3. The inward swinging movement 60 of the finger 69 is effected as follows: The

arm 68 is provided intermediate its ends with an extension 71 which is engaged by a setscrew 72 mounted upon the outer blade of the shears 29 when the shears are swung into wide open position to swing the finger 69 inward against the forward end of the tape, this movement stripping the edge cords and leaving them bare for a sufficient distance to permit the dog 24 to get a clean grip upon the lower cord. When the shears 29 are operated to cut the tape the spring 70 swings the finger 69 out of the way. The cam groove 31 is so designed that after the cutting operation the shears are opened only enough to free them from the tape and swing 75 them out of the path of the dog 24, but not enough to cause contact between setscrew 72 and extension 71. Thus the spring 70 holds the finger 69 out of contact with the tape and permits the dog 24 freely to grip and draw the tape.

The pattern to which the frogs are made is determined by the spacing of the grippers 42 and their associated cams so that by varying the setting of these frogs of any desired 80 pattern, within limits, can be made.

The machine of my invention is capable of producing frogs rapidly, continuously and automatically as long as any tape remains on the spool. Not only can a single operator with one of these machines greatly exceed the output per hour of many hand workers, but the machine-looped frogs are more perfectly made and can be reproduced exactly to any desired pattern.

I claim:

1. A machine for making pyjama frogs from tape having slideable edge cords comprising the combination of means for gripping the tape at a plurality of points along one edge, means for pulling the cord in the other edge to form a loop in the tape, and means synchronized with the pulling means for releasing the gripping means in succession as the loop is formed, the spacing 105 of the gripping means determining the curvature of the loop.

2. A machine for making pyjama frogs from tape having slideable edge cords comprising the combination of means for gripping the tape at a plurality of points along one edge, means for pulling the cord in the other edge to form loops in the tape, and means synchronized with the pulling means for releasing the gripping means in succession as the loops are formed, the spacing 110 of the gripping means determining the curvature and position of the loops.

3. A machine for making pyjama frogs from tape having slideable edge cords comprising the combination of a plate against which the tape lies, a plurality of grippers spaced along the plate for pressing one edge of the tape against the plate to hold the tape against bodily movement, means for 125

pulling the cord in the other edge to form loops in the tape, and means for moving the grippers away from the plate in succession to advance the effective point at which the tape is gripped in the direction of movement of the pulling means, thus determining the curvature and position of the loops.

4. A machine for making pyjama frogs from tape having slidable edge cords comprising the combination of a shaft, a plate paralleling the shaft against which the tape lies, a plurality of cams keyed along the shaft at spaced intervals, a gripper associated with each cam for pressing one edge of the tape against the plate to hold the tape against bodily movement, means operated from the shaft for pulling the cord in the other edge to form loops in the tape, the cams being shaped so as to move the grippers away from the plate in succession to advance the effective point at which the

tape is gripped in the direction of movement of the pulling means, thus determining the curvature and position of the loops.

5. A machine for making pyjama frogs from tape having slidable edge cords comprising the combination of a longitudinal plate, a plurality of grippers spaced along the plate, a carriage, means on the carriage for seizing one of the edge cords, means for moving the carriage across the machine to draw out a unit length of tape between the plate and the grippers, means for causing the grippers to press the other edge of the tape against the plate to prevent further bodily movement thereof, and means synchronized with the carriage for releasing the grippers in succession as further movement of the carriage pulls the free cord, thus forming in the tape loops of predetermined curvature and position.

In testimony whereof I affix my signature.

LOUIS H. MORIN.

CERTIFICATE OF CORRECTION.

Patent No. 1,639,099.

Granted August 16, 1927, to

LOUIS H. MORIN.

It is hereby certified that error appears in the above numbered patent requiring correction as follows: In the grant, heading to the drawings, and throughout the specification, for the word "pyjama" read "pajama"; and that the said Letters Patent should be read with this correction therein that the same may conform to the record of the case in the Patent Office.

Signed and sealed this 20th day of December, A. D. 1927.

Seal.
